J. W. WARREN

CONCRETE SHINGLE

Filed June 11, 1923

John Wright Warren,
McGraw, Attorney

UNITED STATES PATENT OFFICE.

JOHN WRIGHT WARREN, OF ELIZABETHTON, TENNESSEE.

CONCRETE SHINGLE.

Application filed June 11, 1923. Serial No. 644,663.

To all whom it may concern:

Be it known that I, JOHN WRIGHT WARREN, a citizen of the United States, residing at Elizabethton, in the county of Carter and 5 State of Tennessee, have invented certain new and useful Improvements in Concrete Shingles; and I do hereby declare the following to be a full, clear, and exact description of the invention, such as will enable 10 others skilled in the art to which it appertains to make and use the same.

This invention relates to improvements in tiles and more particularly to concrete roofing tiles of the shingle type.

15 One of the objects of the invention is to provide a concrete tile which is ribbed and recessed on its under side in such manner as to provide maximum strength with minimum weight.

20 Another object of the invention is to provide tiles with lap joint portions which will effectively prevent leakage.

A further object of the invention is to 25 provide tiles with depressions in their under sides, the depressions in each tile being adapted to facilitate driving a nail through the tile at a desired point, and the depressions in each tile being positioned in such manner that the tile may be cut into various 30 sections to accommodate hips and valleys and still have one or more depressions to permit a nail to be driven through the remaining section of the tile without fracturing the latter.

35 Another object is to furnish a concrete tile of the above character with an end lug and a recess on its under side near one end of the same to facilitate engagement of the tile with a cleat on a slanting roof.

40 The foregoing are the main objects of the present invention, but other objects are present which will appear in the following description, in which the construction is set forth with reference to the accompanying drawing. In this drawing:

Figure 1 is a vertical sectional view of a portion of a slanting roof with a few of the tiles attached to the same.

Fig. 2 is a top plan view of a few of the 50 tiles in the assembled relation which they will occupy on a roof.

Fig. 3 is a vertical sectional view taken on line 3—3 of Fig. 2.

55 Fig. 4 is a perspective view of one of the tiles.

Fig. 5 is a bottom plan view of the same. Fig. 6 is a detail vertical sectional view taken on line 6—6 of Fig. 2.

As illustrated, the improved tile has a plane upper surface 1, a plane side edge 2 arranged at right angles to the upper surface, and an edge lug 3 which is L-shaped in cross section. This lug has its under surface flush with the bottom surface of the tile but the upper surface of its rib 4 is arranged in a plane below the upper surface 1 of the tile. The lug 3 is of less length than the tile and it reaches from the upper edge 5 to a point 6 spaced from the lower edge 7 of the tile, for a purpose hereinafter described. The edge 2 of the tile forms the side edge of a depending lug or rib 8 which is separated from a longitudinally extending lug 9 on the bottom of the tile, by means of an inverted groove 10. The lug or rib 8 is of a length substantially the same as the lug 3 at the opposite edge of the tile, so that when a number of these tiles are placed with their edges in abutting relation, the downwardly extending rib 8 at one edge 80 of one tile will interlock with the upwardly extending rib 4 of an adjacent tile. The groove 10 has an end wall 11 and this wall forms a downwardly extending lug 12 adapted to engage the end 6 of the rib 3 85 of an adjacent tile, as best shown in Fig. 2. The lug 12 functions to prevent water from moving upwardly between the joint formed by the interlocking ribs 3 and 8 of adjacent tiles and conceals the interlock. 90

The tile is provided on its under side and at its upper end with a transverse end lug or flange 13, which as shown in Fig. 1, is adapted to hang on a cleat 14 on the roof 15. The opposite end of the tile has a depending transverse lug 16, which is adapted to lie snugly on a plane surface and cut off capillary attraction.

The under side of the tile near its upper end is also provided with a transverse 100 groove 17 to accommodate the cleat 14 and permit the tile to lie close to the roof.

In order to diminish the weight of the tile recesses 18 are preferably provided in its under side and these recesses are separated mainly by strengthening ribs 19 and 20. The strengthening rib 19 and the groove 17 are provided with depressions 21, each of which is preferably of cone shape as shown in the drawing. These depressions do not 110

2
extend entirely through the tile but each one terminates close to the upper surface 1. When it is desired to place a nail hole in the tile, the latter is inverted and then a 5 nail may be driven through the tile at either one of said depressions without splitting the tile. Where a full length tile is used, the nail may be driven through at the points where the depressions occur in the groove. 10 17, and then when a tile is placed right side up, a nail 22 may be driven through the tile to secure the same to the roof, as shown in Fig. 1.

In laying the tiles, they are preferably arranged to break joints as shown in Fig. 2, 15 and a row of said tiles is first placed near the lower edge of the roof. The ribs 13 of each of these tiles will hang on the lower-most cleat 14, and the adjacent edges of 20 said tiles will be interlocked by means of the ribs 4 and 8. When the tiles are laid, the lugs 12 will conceal the interlocking joints, as shown in Fig. 3.

From the foregoing it is believed that the 25 construction and advantages of the tile may be readily understood and it is obvious that the details may be altered without depart-

ing from the general construction covered by the claim.

What is claimed and desired to be secured 30 by Letters-Patent is:

A substantially flat concrete tile having plane parallel upper and lower surfaces, the upper surface being unobstructed and unbroken and the lower surface being provided 35 with spaced cavities formed by longitudinal and transversely extending depending ribs, a series of spaced recesses arranged in said longitudinal rib, each of said recesses being of slightly less height than the thickness of the tile and being adapted to facilitate the passage of a nail through the tile at various points even though the tile is sub-divided into a plurality of units, transverse depending flanges extending entirely 45 across the ends of the tile and projecting downwardly below the lower surface, and an L-shaped lug extending outwardly from one side edge of the tile, the opposite side edge portion of the tile having a recess to 50 receive a similar lug of an identical tile.

In testimony whereof I affix my signature.

JOHN WRIGHT WARREN.
